UNITED STATES PATENT OFFICE.

WILLIAM J. DIEDRICH, OF WAUKESHA, WISCONSIN.

SASH-LOCK.

1,036,583.

Specification of Letters Patent. Patented Aug. 27, 1912.

Application filed January 10, 1912. Serial No. 670,438.

To all whom it may concern:

Be it known that I, WILLIAM J. DIEDRICH, a citizen of the United States, residing at Waukesha, in the county of Waukesha and State of Wisconsin, have invented certain new and useful Improvements in Sash-Locks, of which the following is a specification, reference being had to the accompanying drawings.

10 My invention relates to new and useful improvements in sash locks and fasteners and has for its object to provide a device which will lock both sashes, in either their open or closed positions, at one and the same time.

15 A further object of the invention resides in providing means to retain the device in its ineffective position, whereby the sashes may be raised and lowered as ordinarily, 20 and a still further object resides in providing such a device as may be easily applied and one which may be quite readily operated.

25 A further object of the invention resides in providing a device which is adapted for application to the meeting rail of the lower sash and which is designed to project over the meeting rail of the upper sash and still another object of the invention resides in 30 the provision of a double locking bolt which is movable laterally of the device so as to engage the side molding of the one sash and the side rail of the window casing thereby causing the sashes to bind tightly against 35 the casing and preventing undue separation of the meeting rails of the sashes.

40 Another object of the invention resides in providing a device which is extremely simple and durable in construction, inexpensive to manufacture, and one which will be very efficient and useful in operation.

45 With these and other objects in view, my invention consists in the novel features of construction, combination and arrangement 50 of parts as will be hereinafter referred to and more particularly pointed out in the specification and claim.

55 In the accompanying drawing forming a part of this application, Figure 1 is a perspective view showing my device applied to use. Fig. 2 is a horizontal section through the device and a portion of the window casing, and, Fig. 3 is a perspective view of the locking bolt removed.

55 In carrying out my invention, I shall refer to the drawing in which similar reference

characters designate corresponding parts throughout the several views and in which 1 indicates a window casing or frame, within which is slidably mounted the upper and lower sashes 2 and 3, respectively, said sashes being separated from one another in the casing 1 by the usual dividing strip or bead 4. A casing or housing 5 formed preferably of wood having a removable top 6 thereon, is secured to the upper frame of the lower sash 3 by means of the screws or the like 7, and the one side and end of this housing or casing is offset to provide square shoulders 8 and 9, respectively, the offset portion forming the shoulder 8 being adapted to receive therein the dividing strip or bead 4, while the other offset portion forming the shoulder 9, is adapted to receive the one side frame of the upper sash 2. A solid 70 portion 10 formed in the one end of the housing or casing 5 separates a pair of channel-ways or the like 11 and 12, respectively, the one channel-way 12 continuing through the shoulder 9, while the channel-way 11 75 continues through the one end of the casing, while both of said channel-ways terminate at their opposite ends and their hollow portion 13 at the other end of the casing or housing 5.

80 A locking bolt 14 of substantially V-shape, is provided and mounted in the casing 5 so that the two arms thereof are disposed, respectively, in the channels 11 and 12, while the connection of the two arms thereof is 85 disposed in the hollow portion 13, and the dependent stem 15 of the bolt disposed through a slot or opening 16 in the one end of said casing. The two bifurcated or spaced arms of the bolt 14 are designed 90 coincident to the channels 11 and 12 so that one is considerably longer than the other, in view of the offset portion on the one side of the casing, and in order to dispose the bolt normally in such position as to 95 permit the ends of the arms to project through the openings in the end of the casing, a coil spring 17 is provided and encircled about the stem 15 of the bolt between the one end of the casing and the junction of the arms of said bolt. The 100 tendency of this spring will be to force the free ends of the arms of said bolt through the openings formed by the channel-ways 11 and 12 and the end of the casing, and 105 in order to withdraw the bolt against the tension of the spring, for a purpose to be

hereinafter and more particularly described, I provide a knob or finger piece 18 on the free end of the stem 15 of said bolt.

A pair of metallic strips 19 and 20 are, respectively secured, in any desired manner, to the one side rail of the casing 1 and the adjacent side frame of the upper sash 2, said strips being provided with a plurality of openings 21 which align with one another and register with sockets or openings 22 in the casing and sash frame, and the casing 5 with its locking bolt carried therein, is so designed and applied to the lower sash 3 as to dispose the one side thereof over the lower frame of the upper sash and permit the two arms of the locking bolt to align with the line of openings in the respective strips 19 and 20. Thus, it will be seen that the arms of the bolt 14, as they are forced outwardly by the tendency of the spring 17, are adapted to enter the openings 21 of the strips 19 and 20 and simultaneously lock the respective sashes in any adjusted position with respect to one another. The normal tendency of the spring 17, as stated above, is to force the bolt outwardly, and in order to retain the bolt in its ineffective position so that the sashes may be raised or lowered regardless of the sash lock, I provide the longer arm of the bolt 14 with a plurality of notches or teeth 23, while pivotally disposed in a slot 24 in the one side wall of the casing 5, is a pawl 25. The effective end of this pawl is adapted to engage the teeth or notches 23 in the one arm of the bolt, to retain said bolt in its ineffective position, and the pawl, itself, is manually operable by a finger piece 26 formed on the opposite end thereof and which is designed to project beyond the one side wall of the casing 5.

In operation, it will be seen that after the device has been set up and applied to the upper frame of the lower sash of the window and the strips 19 and 20 properly applied to the casing and upper sash, respectively, in alinement with the arms of the locking bolt, said device may be permitted to effectively lock the sashes in their closed positions, as shown in Fig. 1, by merely permitting the locking bolt to project beyond the casing through the tendency of the spring 17. As above stated, the openings in the strips 19 and 20 are disposed in alinement with one another and as they are so arranged as to be received by the arms of the locking bolt at the time the two sashes are in their closed position, it will be seen that said sashes may be held locked in this position. Should it be desired to raise the lower sash, regardless of the position of the upper sash, the same may be accomplished by merely drawing the bolt outwardly by grasping the finger piece 18 and raising the sash to the desired height.

whereupon the bolt may be released and the arms thereof again engaged with the alining openings in the strips 19 and 20. When it is desired to lower the upper sash, vice versa is true, or both the upper sash and lower sash may be lowered and raised, respectively and then locked in their adjusted positions in the same manner, as above described. Thus, it will be seen that in no matter what position either the upper or lower sash may be, both may be locked and prevented from further movement until the release of the locking bolt 14. Should it be desired to eliminate the use of this sash lock entirely so that the sashes may be raised or lowered without notice being given to this device, the same may be ineffectively disposed by merely withdrawing the locking bolt and engaging the effective end of the pawl 25 with the teeth 23 on the one arm of the bolt. Whenever it is again desired to place the sash lock in use, it is only necessary to release the engagement of the pawl 25 with the teeth 23, whereupon the spring 17 will force the ends of the arms of the locking bolt outwardly to engage the openings in the strips 19 and 20.

By providing a housing which when secured to the meeting rail of the lower sash has a portion thereof projecting over the meeting rail of the upper sash, and by providing a locking bolt which is movable laterally of the housing, it will be seen that the rattling of said sashes will be prevented, since the same will be caused to bind against the casing or window frame. Furthermore the lateral movement of the locking bolt does not force the meeting rails of the sashes apart but simultaneously causes the same to bind against the one side of the casing and, in fact, retains said meeting rails together, thereby preventing the wind from blowing therethrough. It will still further be seen that by permitting the housing to project over the meeting rail of the lower sash, and providing a double locking bolt, the arms of which are projected over the meeting rails of the respective sashes, the malicious picking of said lock will be practically impossible.

From the foregoing, it will be seen that I have provided simple, inexpensive and efficient means for carrying out the objects of the invention, and while the elements described are most well adapted to perform the functions set forth, it is obvious that various changes in form, proportion and in the minor details of construction may be resorted to without departing from the spirit or sacrificing any of the principles of the invention.

What I claim is:—

In a sash lock of the class described, the combination with a window casing and an upper and lower sash slidably mounted

therein; of a housing applied to the upper face of the meeting rail on said lower sash, the front and rear ends of said housing being projected beyond the front and rear 5 faces of said meeting rail to dispose a portion of the same over the meeting rail of said upper sash, a pair of metallic keeper strips secured respectively to the one side rail of the upper sash and the wall of said 10 casing forward of said lower sash, said strips being provided with a plurality of openings therein, a U-shaped locking bolt inclosed within said housing and slideable laterally therein, the arms of said bolt being 15 of unequal lengths and adapted to project through the one side of said housing to respectively engage the openings in the keeper strips on the wall of said casing and the side rail of the upper sash, a stem carried on the base of said U-shaped bolt and projected 20 through the opposite side of said housing, the projected portion of said stem being disposed over the meeting rail of the lower sash, whereby the same may be readily grasped to operate said bolt, a coil spring 25 encircling said stem between the base portion of said bolt and the one side wall of said housing to normally dispose said bolt in its effective position, and means to retain said locking bolt in its withdrawn and 30 ineffective position.

In testimony whereof I hereunto affix my signature in the presence of two witnesses.

WILLIAM J. DIEDRICH.
